UNITED STATES PATENT OFFICE.

WILLIAM A. TAYLOR AND COLUMBUS M. GIDLEY, OF BORGER, TEXAS.

PLACARD SUPPORT FOR TANK CARS.

Application filed December 15, 1927. Serial No. 240,280.

This invention relates to devices for supporting placards upon cars, and particularly for supporting placards upon tank cars showing whether or not the tank car is filled, or 5 in other words contains inflammable material, and while the invention is particularly designed for use with tank cars transporting gasoline and other highly inflammable and volatile liquids, we do not wish to be limited 10 to this use as the same device might be used upon cars for supporting placards for other purposes.

The general object of the present invention is to provide a placard supporting member 15 and a fixed shield, and provide means whereby the placard supporting member may be disposed in position behind said shield and entirely obscured thereby as, for instance, when the car does not contain inflammable 20 material, or whereby the placard may be shifted into a position in front of said shield, thus entirely obscuring the shield but displaying the placard stating that the car does not carry inflammable or explosive material.

25 A further object is to provide means whereby the first named placard may be locked in either of its adjusted positions, and provide means whereby the placard may be concealed in this position so as to prevent any unauthorized tampering with the placard.

30 A further object is to provide a device of this character including a support adapted to be attached to the running board of a tank car, provide a fixed shield mounted upon the support, and provide a movable placard support rotatably shiftable from a position occulted by the shield to a retracted position and then movable into a position in advance of the shield and then rotated to a position 40 directly in front of the shield.

Our invention is illustrated in the accompanying drawings, wherein:

Figure 1 is a front elevation of a placard support constructed in accordance with our 45 invention and displaying fixed placard or shield;

Figure 2 is a side elevation of the structure shown in Figure 1;

Figure 3 is a rear elevation of the structure shown in Figures 1 and 2;

Figure 4 is a fragmentary section showing the connection of the rock shaft to the placard-supporting arm;

Figure 5 is a front elevation of the structure shown in Figure 1 but with the remov-

able placard disposed in front of the fixed placard;

Figure 6 is a like view to Figure 2 but showing a different position for the movable placard;

Figure 7 is a rear view of the structure shown in Figure 6;

Figure 8 is a fragmentary detail elevation of the lower end of the placard-supporting arm 19.

Referring to these drawings, it will be seen that 10 designates a supporting bracket which is somewhat U-shaped in form and has its arms depending. One of these arms 11 is relatively short. The other arm 12 is 70 relatively longer than the arm 11 and at its lower end is inwardly bent, as at 13, and then upwardly extended, as at 14. This bracket 10 has riveted to it or otherwise attached to it the plates 15 which are designed to fit 75 against the bottom of the running board of a tank car and be attached thereto by riveting, bolting or any other suitable means.

Riveted upon the upwardly extending portion 14 is a laterally and upwardly curved 80 extension 16 which extends upward nearly to the level of the top of the bracket and then extends laterally as at 17. This extension is welded to a plate 18 which forms part of an upwardly extending supporting bar 19. The 85 upper end of the extension 16 and the plate 18 are both formed with a relatively large aperture 20 extending through these two members. Riveted to the vertically extending bar 19 is the shield 21 which is preferably square in form, though not necessarily limited to this form, and is disposed with two corners of the square in a vertical line. It will be seen that the bar 19 is rigidly engaged with the member 16 which forms an 90 extension of a portion 14 of the bracket, the extension being riveted to this portion 14 by the rivets or bolts 22.

Oscillatably mounted in the portions 11 and 12 of the bracket 10 is a rock shaft 23, 100 the front end of which is provided with a handle 24. This rock shaft is mounted to oscillate within the members 10 and also to slide in the members 10. The extremity of this shaft 23 is tapered and squared at 25 105 and terminates in a screw-threaded portion carrying the nut 26. Mounted upon this squared and tapered end is an arm 27, which arm carries upon it the target or placard 28 which may be made of sheet iron like the 110

shield 21 and which is riveted to the arm. Of course, we do not wish to be limited to the material of the shield or of the placard. The arm 27 below the shield carries the inwardly projecting pin 29 which, when the arm 27 confronts the arm or bar 19, will enter the aperture 20 previously referred to and acts as a locking bolt.

Attached to the rear or inner face of the portion 12 of the bracket 10 is a downwardly, laterally and rearwardly curved supporting rest 31 which extends downward to a point slightly below the pivotal center for the arm 27. Extending through the portion 12 of the bracket 10 and through the arm 19 is a bolt or pin 32 whose extremity is reduced and screw-threaded for engagement with the portion 12. This member 32 is disposed on the opposite side of the arm 19 from the rest 31 and above the level of this rest.

The shaft 23 is urged forward by means of a coiled spring 33 which surrounds the shaft 23 and bears at one end against the portion 12 of the bracket 10 and at the other end against a washer 34, this washer being held in place by a cotter pin 35. The shaft 23 is formed with two apertures 36 and 37 and a pin 38 is adapted to be disposed in either of these apertures.

In the use of this device, assuming that the placard 28 is disposed behind the shield 21 and that it is desired to display the placard 28, then the pin 38 is removed and the shaft 23 pushed inward sufficiently far to carry the pin 29 out of locking engagement with the aperture 20 in bar 19. The shaft may then be rocked in a counter-clockwise direction to swing the arm 27 and the placard 28 downward until the arm rests upon the support 31. At this time the placard 28 has moved entirely beyond the shield 21 and the shaft may be pulled forward or allowed to move forward under the action of the spring 33. When it is moved sufficiently forward, the shaft is again rotated, this time in a clockwise direction, which carries the placard 28 up in front of the shield 21, as shown in Figure 2. The arm 27 cannot move forward any faster than is permitted by the curved support 31, but when the arm 27 has reached a vertical position the pin 29 will be directly opposite an opening 20^a formed in the portion 12 of the bracket 10 and the pin 29 will enter this opening 20^a and again lock the placard in a vertical position, this time with the placard entirely obscuring the shield. When this has been accomplished the pin 38 may be then again inserted through the opening 36, which will prevent inward movement of the shaft, and thus prevent the placard supporting arm from being removed from its locked position. Preferably the portion 11 of the bracket is formed with an aperture 39, as is the end of the pin 38, through which a sealing wire may be

passed so as to lock the pin 38 in place against accidental removal.

It will be understood that while we have referred to the part 21 as a shield and the part 28 as a placard that this is merely to differentiate between these two elements but that, as a matter of fact, the part 21 will also constitute a placard or sign and will preferably have thereon words denoting that the car is empty, while the placard 28 will have thereon words denoting that the car is full. These signs might be reversed, however. The point is that when the member 28 is behind the member 21, the member 21 will be displayed whether this member 21 be entirely blank upon its face or contain signs or symbols, and that when the member 28 is shifted in front of the member 21, the member 21 will be occulted and if there are any signs or symbols upon the member 28 these will be displayed.

It will be seen that we have provided very simple means whereby one or the other of two placards may be displayed and locked in this display position, that this placard apparatus may be readily operated from the side of the car, and that the placard device fully complies with the law regarding the placarding of tank cars or cars carrying explosive materials. While preferably the elements 21 and 28 will be made of metal as, for instance, thin sheet metal which is flanged at its margins, we do not wish to be limited to this. The signs, symbols or other directions may be painted upon these elements or printed matter may be pasted thereon.

While we have illustrated certain details of construction and arrangement of parts which have been found to be particularly effective for the purpose intended, we do not wish to be limited thereto as many changes might be made therein without departing from the spirit thereof as defined in the appended claims.

We claim:

1. A sign support for railway cars comprising a supporting bracket, a shield rigidly supported thereon and extending upward therefrom, a placard mounted upon the bracket for oscillation in a plane parallel to the plane of the shield or for bodily movement at right angles to the plane of the shield, and manually operable means for oscillating said placard into or out of a position confronting the shield, said means being manually shiftable to shift the placard at right angles to the plane of the shield.

2. A sign supporting device for railway cars comprising a bracket, a shield rigidly supported upon the bracket and extending vertically upward therefrom, a shaft extending through the bracket and below the shield, said shaft being longitudinally movable through the bracket and rotatably

mounted therein, and a placard mounted upon and carried by the shaft, and means for locking the shaft with the placard disposed behind the shield or in front of the shield.

5 3. A sign supporting device for railway cars comprising a bracket, a shield rigidly supported upon the bracket and extending vertically upward therefrom, a shaft extending through the bracket and below the shield, said shaft being longitudinally movable from the bracket and rotatably mounted therein, a placard mounted upon and carried by the shaft, and means for locking 10 the placard against oscillation when in a position either behind the shield or in front of the shield.

15 4. A sign displaying device for cars comprising a bracket adapted to be mounted upon a car, a shield extending upward from the bracket and rigidly engaged therewith, a supporting bar for the shield having an opening, the supporting bar for the shield being spaced from the bracket and the bracket having an aligning opening, a shaft passing through the bracket below the shield, the shaft being longitudinally and rotatably movable in the bracket, a placard mounted upon the shaft and movable therewith both 20 laterally from the shield and in a plane at right angles to the plane of the shield, the placard including a supporting arm having a pin insertible into the opening of the arm supporting shield or into the opening of 25 the bracket, and a spring urging the shaft in a direction to shift the pin on the placard arm into either one of said openings.

30 5. A sign displaying device for cars comprising a bracket approximately U-shaped in form, one of the arms being extended below the other arm and then extended rearward and upward, a shield mounted upon said upwardly extending arm, a shaft passing through the bracket to one side of said 35 upwardly extending arm, the shaft being rotatable and longitudinally shiftable in the bracket, a placard mounted upon the shaft for rotational movement from a position in alignment with the shield to a position out 40 of such alignment or vice versa and being movable with the shaft from a position behind the shield to a position in front of the shield, and means for locking the parts with the placard in a position of alignment 45 with the shield.

50 6. A sign display device of the character described comprising a bracket, a shield, a rock shaft passing through the bracket and having a handle at one end, the opposite end 55 of the rock shaft carrying a placard supporting arm, the shaft being longitudinally shiftable through the bracket or rotatably shiftable therein, a shield supported by the bracket with its center disposed vertically 60 above or disposed in line with the shaft

whereby the shaft may be rotated to shift the placard into a position of registry with said shield, the placard being thus movable by the shaft from a position behind the shield to a position out of registry with the shield, 70 then to a position in front of the shield, and again to a position in registry with the shield or vice versa, and resilient means locking the parts in either of said positions.

75 7. A sign supporting device for cars comprising a supporting bracket, a shaft passing therethrough and having a handle at its forward end, a spring urging said shaft forward, an arm mounted upon the rear end of the shaft and carrying a placard, an arm fixedly mounted upon the bracket and extending upward therefrom and carrying a shield the same size as the placard, means carried by the arm for locking the placard and arm against lateral movement when 80 the placard has been turned into registry with the shield either in front of the shield or behind the shield, said means being actuated by a forward movement of the shield and its supporting arm due to the spring 85 acting on said shaft.

90 8. A sign supporting device for cars comprising a supporting bracket, a shaft passing therethrough and having a handle at its forward end, a spring urging said shaft forward, an arm mounted upon the rear end of the shaft and carrying a placard, an arm fixedly mounted upon the bracket and extending upward therefrom and carrying a shield the same size as the placard, means 95 carried by the arm for locking the placard and arm against lateral movement when the placard has been turned into registry with the shield either in front of the shield or behind the shield, said means being actuated by a forward movement of the shield and its supporting arm due to the spring 100 acting on said shaft, and releasable means for locking the shaft from inward movement against the action of said spring.

105 9. A sign display device for tank cars comprising a supporting bracket having depending front and rear arms, the rear arm being longer than the front arm and having an upward extension at its rear end, a shaft 110 passing through the arms of the bracket, a spring urging the shaft axially forward, said extension being out of line with the shaft to permit the shaft to be shifted past the plane of the extension, a sign mounted on said extension, an arm mounted upon the shaft, a sign carried by the arm and adapted to be swung by an oscillation of the shaft into or out of a position of registry with the first named sign and shifted into position in front of or rearward of the first named sign by a longitudinal movement of the shaft, a pin carried by said arm, the rear arm of the bracket and the arm of the fixed sign being 115 apertured for engagement by said pin where- 120

by to lock the shiftable sign in its fully shifted positions.

10. A sign display device for tank cars comprising a supporting bracket having front and rear depending arms, the rear arm being longer than the front arm and having an upward extension at its rear end, a shaft passing through the bracket and oscillatably and longitudinally movable therein, a spring urging the shaft axially forward, said extension being curved to extend around the path of movement of the shaft, a sign rigidly mounted upon the extension, a second sign mounted upon the shaft and adapted to be swung by the shaft into or out of registry with the first named sign, the second named sign being movable longitudinally with the shaft, stops with which the swinging sign engages at the end of its lateral movement, and means for locking the shaft against longitudinal movement.

11. A sign display device comprising a support, a vertically disposed shield rigidly mounted upon the support and extending upward therefrom, a manually shiftable sign shifting means mounted upon the support for movement in longitudinal and transverse planes, a sign rigidly mounted upon the sign shifting means and extending upward therefrom and movable by the sign shifting means into or out of a position in advance of or rearward of the shield and shiftable by the sign shifting means into or out of a position of registry with the shield, and means

for locking the movable sign in either of its fully shifted positions.

12. A sign display device comprising a support, a vertically disposed shield rigidly mounted upon the support and extending therefrom, a manually shiftable sign shifting means mounted on the support for movement in longitudinal and transverse planes, a sign rigidly mounted upon the sign shifting means and movable by the sign shifting means into or out of position in advance of or rearward of the shield and shiftable by the sign shifting means into or out of a position of registry with the shield, the sign shifting means at all times supporting the sign in a plane parallel to the plane of the shield.

13. A sign display device comprising a support, a vertically disposed shield rigidly mounted on and extending upward from the support, a manually shiftable sign shifting means mounted upon the support below the shield for movement in longitudinal and transverse planes, a sign rigidly mounted upon the sign shifting means and extending upward therefrom and movable with the sign shifting means into or out of a position in advance of or rearward of the shield and shiftable by the sign shifting means into or out of position of registry with the shield.

In testimony whereof we hereunto affix our signatures.

WILLIAM A. TAYLOR.
COLUMBUS M. GIDLEY.
